FLUSH VALVE

William H. Cadwell and John Ott, New Britain, Conn., assignors to The Beaton & Cadwell Manufacturing Company, New Britain, Conn., a corporation of Connecticut

Application July 20, 1932, Serial No. 623,518

1 Claim. (Cl. 137—93)

This invention relates to valves, and more particularly to a flush valve which will produce the same period of flush irrespective of the length of time the actuating handle is pressed down.

5 One object of the invention is to provide a flush valve of the above nature which will deliver only a single flush even though the actuating handle is held down continuously or is operated several times in quick succession.

10 Another object is to provide a flush valve of the above nature having a tilttable mushroom-shaped release valve provided with a depending detachable sleeve bushing within which is slidably fitted a valve stem movable relative to said release valve.

15 A further object is to provide a flush valve of the above nature which will be simple in construction, inexpensive to manufacture, easy to install and manipulate, fool-proof, compact, ornamental in appearance, and very efficient and durable in use.

With these and other objects in view there has been illustrated on the accompanying drawing one form in which the invention may be conveniently embodied in practice.

In the drawing:

Fig. 1 represents a vertical longitudinal sectional view of a flush valve embodying the invention.

30 Fig. 2 is a side view of the flush valve shown on a somewhat reduced scale.

Fig. 3 is a fragmentary sectional view through the adjusting valve mechanism, the view being taken along the line 3—3 of Fig. 2.

35 Fig. 4 is a separated detail perspective view of the mushroom valve construction.

Fig. 5 is a fragmentary sectional view on a reduced scale, showing the relation of the parts after the actuating handle has been tripped.

40 This invention is an improvement over the patent application filed August 12, 1930, by H. F. Kelso, Serial No. 474,777.

45 Referring now to the drawing in which like reference numerals denote corresponding parts throughout the several views, the numeral 10 indicates the body member of the flush valve having a horizontal side inlet port 11 and a bottom vertical outlet port 12. The side inlet port 11 is adapted to be connected to a water supply pipe, not shown, by means of a threaded nipple 13 and a cooperating coupling nut 14.

50 The top of the outlet port 12 terminates in a thin interior rim 15 forming a seat for a hollow main valve consisting of an upper flanged bushing 16 and a lower sliding sleeve 17 screwed

upon the lower end of said bushing. The sleeve 17 is preferably provided with a plurality of vertical guiding vanes 18 adapted to slidably fit within the reduced section 12a of the outlet port 12. The bushing 16 has an integral horizontal flange 19 which is threaded on its outer edge.

5 The space within the upper part of the flush valve is divided into two chambers which will hereinafter be termed the "main chamber" 20 and the "control chamber" 21. The chambers 20 and 21 are separated by means of a flexible diaphragm 22 preferably constructed of rubber. The inner portion of the diaphragm 22 is provided with an enlarged annular depending section 22a which is adapted to be held tightly between the upper flanged bushing 16 and the lower sliding sleeve 17 of the main valve, and a portion of said annular section 22a rests upon the top of the rim 15 for normally closing the outlet port 12.

10 The diaphragm 22 is provided with an outer horizontal annular flange 22b disposed between the top face of an enlarged annular threaded rim 23, forming an integral part of the body 10, and another annular flange 24 forming the integral base of a dome-shaped cover 25. The annular diaphragm rim 22b and the cover flange 24 are properly indexed in relation to the body member 10 by means of a pair of dowel pins 26 secured to said cover flanges 24 and adapted to project through corresponding holes in said diaphragm flange 22b into corresponding sockets 27 formed in the body rim 23.

15 The "dome" cover 25 forms the top closure of the control chamber 21, while the rubber diaphragm 22 forms the bottom closure, as clearly shown in Fig. 1. The "dome" cover 25 and the diaphragm 22 are both clamped against the top seat of the body rim 23 by means of an upper casing member 28 having a depending tapped skirt 29 engaging the threaded rim 23, said casing member 28 having a hexagonal nut 30 integral with its top portion for convenience in manipulation.

20 In order to permit the release of a small quantity of water from the control chamber 21 to cause the pressure in the main chamber 20 to lift the main valve and start the flushing stream, provision is made of a mushroom head valve unit 31. This unit 31 comprises a slightly cupped horizontal valve head 32 located in the control chamber 21, a detachable intermediate tubular sleeve bushing 33, and a vertical slidably stem 34 depending from said sleeve bushing member 33. The underside of the valve head 32 is provided with an annular beveled rib 35 adapted to seat 25

25 upon the lower end of the main valve bushing 16. The top of the stem 34 is provided with a shoulder 36 which rests upon the top of the diaphragm 22, and the stem 34 is secured to the body 10 by means of a set screw 37.

upon a sealing gasket 36, preferably constructed of rubber. The gasket 36 is supported upon the upper face of the horizontal flange 19 of the bushing 16 and held in place by a heavy flanged tapped ring 37 screwed upon the threaded outer edge of said flange 19. An adjustable headless set-screw 38 is screwed into the upper part of the valve head 32 and is adapted to strike against the underside of the dome cover when the main valve rises.

10 As clearly shown in Fig. 4, the underside of the valve head is formed with a tapped socket 39 for detachably receiving the upper threaded end of the tubular sleeve bushing 33. The sleeve bushing 33 is provided with a pair of opposed flat sections 40 to which a wrench may be applied in assembling the valve. The upper part of the vertical stem 34 is provided with an integral enlarged head 41 slidably fitted within an interior chamber 42 formed within the sleeve bushing 33, and

15 said stem 34 is supported by an inturned flange 43 formed at the bottom of said bushing. Just above the flange 43, the bushing is provided with a pair of opposed radial apertures 44, and the enlarged head 41 of the stem 34 has a pair of opposed vertical grooves 45 which serve to permit the stem 34 to move freely up and down within said bushing 33.

For the purpose of tilting the stem 34 to one side for unseating the mushroom valve 31 and starting the valve in operation, provision is made of a horizontal plunger rod 46 located in alignment with the lower end of the valve stem 34. The rod 46 is slidably fitted within a threaded nipple 47 screwed into a tapped boss 48, extending laterally from the side of the body member 10. The plunger rod 46 terminates at its outer end in an enlarged piston head 49 which is adapted to slide in a cylinder 50. The piston head 49 is normally pressed against a tiltable head 51 by the influence of a helical compression spring 52 axially disposed about the plunger rod 46 and confined within the cylinder 50. The tiltable head 51 forms part of an operating handle 53 normally lying in a horizontal position, as shown in Fig. 1, and said head 51 is universally pivoted within a shouldered recess 54 located in back of an inturned end 55 forming the integral front end of a union 56.

By means of this construction, it will be seen that when the handle 53 is swung in any direction, the head 51 will tilt in the recess 54, as shown in Fig. 5, and cause the plunger rod 46 to slide inwardly and strike against the depending stem 34 causing it to move to one side. This action will unseat the valve head 32 and start the flushing stream.

55 In order to restore the pressure in the control chamber 21 after the flush valve has been operated, provision is made of an adjustable bypass valve plug 57 retained within a lateral hollow boss 58 by means of a threaded ring 59, the adjustment and operation of said plug 57 being fully described in the previous patent to the above inventors, No. 1,657,817. The plug 57 has a central horizontal passage 60 communicating with the main chamber 20 and a vertical passage 61 adapted to be selectively joined to a short vertical bleed hole 62 in the body member 10. The bleed hole 62 leads into an upper enlarged chamber 63 having a small check valve plug 64 located at its upper end, within which plug 64 a ball check valve 65 is seated. The ball check valve 65 serves to prevent back siphonage in case the pressure in the inlet port 11 should fall below normal, but does not interfere with the action of the bypass.

70 The annular flange 24 of the domed cover 25

is provided with a short horizontal hole 66 leading into the interior of the check valve plug 64 and completes the bypass between the upper control chamber 21 and the lower main chamber 20.

Operation

Whenever it is desired to operate the flush valve, the handle 53 will be rocked in any desired direction, causing the plunger rod 46 to move inwardly, and strike against the vertical stem 34, 10 rocking the mushroom valve head 32 off of its seat. A small quantity of water will thus be allowed to escape from the control chamber 21 reducing the pressure therein below that existing in the main chamber 20.

15 The greater pressure below the flexible diaphragm 22 will then quickly force the main valve upwardly off of its seat and will open communication between the inlet port 11 and the outlet 12. The main valve will be guided within the 20 outlet port 12 while rising to open position by the vanes 18, and will force the mushroom valve 39 upwardly until the adjustable screw 38 on the top thereof strikes the dome 25 covering the control chamber 21. The annular rib 35 on the bottom 25 of the valve head 32 will thus be caused to press tightly down upon the gasket 36 on top of the main valve, thereby closing the direct passage between the control chamber 21 and the main chamber 20 through the main valve.

30 The main valve will remain raised to permit the unrestricted flow of the flushing stream until the pressure in the control chamber 21 has been restored to normal by the slow leakage of water thereinto from the main chamber 20 through the 35 restricted bypass. Since the pressure in the two chambers will then be equalized, the main valve will then close, due to its weight and the resiliency of the rubber diaphragm 22. The flushing stream will be thereby shut off. If the operating 40 handle is held down continuously, the stem 34 will be held up in the position shown in Fig. 5, thus insuring against more than a single flush being made.

45 While there has been disclosed in this specification one form in which the invention may be embodied, it is to be understood that this form is shown for the purpose of illustration only, and that the invention is not to be limited to the specific disclosure but may be modified and embodied 50 in various other forms without departing from its spirit. In short, the invention includes all the modifications and embodiments coming within the scope of the following claim.

Having thus fully described the invention what 55 is claimed as new and for which it is desired to secure Letters Patent is:

In a flush valve, a valve casing having inlet and outlet ports, a movable main valve adapted to divide said casing into a main chamber and a control chamber, a release valve carried by said main valve for normally forming a seal between said chambers, said release valve having a tapped bottom socket and being tiltable with respect to said main valve, said release valve having an adjustable depending threaded sleeve screwed into said tapped socket, said sleeve having a pair of opposite parallel flat vertical faces for permitting it to be turned by a wrench, the bottom of said sleeve being inturned to form an annular seat, a stem slidably fitted without back-lash within said seat and in liquid-tight relation therewith, said stem having a cylindrical head provided with a close sliding fit within said sleeve and adapted 75

to rest upon said annular seat, said head having a plurality of vertical peripheral grooves, said sleeve having a plurality of apertures immediately above said inturned seat to permit the free circulation of air and water therethrough and reduce the frictional resistance opposing the free relative movement between said sleeve and said stem, and manually operated means for striking

said stem to cause said release valve to rock off of its seat on said main valve to operate the flush, whereby said release valve will be positively allowed to close without sticking after the proper interval of flush irrespective of the time which the operating handle is held down.
